UNITED STATES PATENT OFFICE.

ARTHUR SCHÄFFER, OF DUBUQUE, IOWA.

MUSIC-RACK.

Specification forming part of Letters Patent No. 89,084, dated April 20, 1869.

To all whom it may concern:

Be it known that I, ARTHUR SCHÄFFER, of Dubuque, in the county of Dubuque and State of Iowa, have invented a new and Improved Music-Rack; and I do hereby declare that the following is a full, clear, and exact description thereof, reference being had to the accompanying drawings, making part of this specification, in which—

Figure 1 is a perspective view of my improved music-rack opened and ready for use as a support for sheet-music. Fig. 2 is a perspective view of the rack closed. Fig. 3 is a front view of the rack open.

Similar letters of reference indicate corresponding parts in the several figures.

This invention is designed to afford a portable rack or holder for sheet-music or other printed or written, bound or unbound matter, which rack is so constructed of sections jointed together as to fold into a very small compass, and which is provided with means for supporting the sections in proper position when unfolded, as will be hereinafter explained.

To enable others skilled in the art to understand my invention, I will describe its construction and operation.

In the accompanying drawings, A A represent two sections of equal length, which are pivoted to one end of a section, B, of similar length, and constructed of right-angular shape in cross-section, so as to afford, when folded, as shown in Fig. 2, a case for receiving the other sections composing the rack, and when opened, as shown in Figs. 1 and 3, to afford a ledge for supporting the lower edge of a piece of sheet-music or other unbound or bound matter. For the purpose of holding the right-angular pieces A A in place when folded against the central piece, B, pins i i are fastened to the said pieces A A, which pins are received by perforations made in the edges of this central piece, and which will hold the pieces together by friction with sufficient security for all practical purposes. Instead of depending upon these pins i i for this purpose, hook-fastenings or a rubber band applied to the rack when folded will keep the parts in place. The pins i i are more particularly used for keeping in place and forming attach-

ments for the side pieces, c c, of the rack, as shown in Figs. 1 and 2. When the pieces A A are opened to their fullest extent, their pivoted ends will abut, and the central piece, B, will be perpendicular to these pieces, and form a central standard for the upper sections, C C, of the rack, as shown in Figs. 1 and 3. The two sections C C are pivoted at d d to the free end of the standard B, and to their outer free ends the sections c c are pivoted, so that when adjusted, as shown in Figs. 1 and 3, they serve, in conjunction with the central standard, B, as a frame or back support for sheet-music or other printed or written matter. Each one of the strips C C c c is equal in length to the sections A A B, and these strips are so connected by joints that they can be folded over the standard B, and received in the place formed by the two base pieces A A, when these two pieces are shut, as shown in Fig. 2.

By thus hinging together the several pieces composing the rack, it will be seen that they can be folded closely together into a space equal in length to the length of one section B, and thus made so small as to be very portable and convenient for carrying in the pocket.

To erect the rack, the two sections A A are adjusted in a straight line, the two sections C C are spread out in a straight line parallel to A A, and the two end sections, c c, are turned down perpendicular to A C, and their ends attached by pins i i to the base-pieces A A, thus forming a rectangular frame. This frame is supported in an inclined position by means of a prop, E, and a piece, D. The prop is half the thickness of the standard B, and is pivoted at its upper end in a slot made in this standard and constructed with a pin, p, on its free end. The piece D is pivoted at the base of the slot in standard B, and is also about half as thick as this standard, so that by adjusting the two pieces E D in line with their standard they will not occupy a space greater than the thickness of this standard, and by adjusting the two pieces, as shown in Fig. 1, and inserting the pin p of the prop E into one of several holes through the piece D, a good back support for the frame will be afforded.

The sections constituting the improved rack are preferably made of hard wood; but, if desirable, they may be made of metal.

Having described my invention, what I claim as new, and desire to secure by Letters Patent, is—

1. The construction of the base of a portable rack of right-angle strips A A, united by pivots to a central standard, in combination with hinged pieces C C and pins *i i*, arranged substantially as described.

2. The slotted standard B, having pivoted in its slot the perforated piece D and prop E, and having pivoted to its ends the pieces C C and A A, substantially as described.

ARTHUR SCHÄFFER.
